Assignors to

Cox, Warren, Morrison & Co. of Troy, N.Y
Letters Patent N° 764. Dated Feb. 12, 1856.

The schedule referred to in these Letters Patent, and making part of the same.

120
Ms. 764

To all whom it may concern,

Be it known that we, Samuel Pierce, of Troy, in the County of Rensselaer, of State of New York, & J. J. Dulley, of Yonkers, in the County of Westchester, in the same State, have invented or produced a new & original design of Cook Stove, which we call the "Gothic Air Tight"; & we do hereby declare that the following is a full, clear, & exact description of the same reference being had to the annexed perspective drawing, making a part of this specification.

The nature or peculiarity of our design of Cook Stove, consists as follows: viz:-

A, is the jamb plate, decorated at top & bottom with the ornamental moldings (a & b) & plain molding (c) B.B. are oven doors, ornamented on their panels with the Gothic ornaments (d & e) C, is the fire door, with ornament (f) on the panel. D. D. are the front doors, & front upper plate, the doors are ornamented with the Gothic molding &c (g.g.) E, is the lower front plate with the raised ornamental panel F, G is the hearth plate with ornamental border (h) around it. H, is the top plate with molding (i) around the edges. I, is the bottom plate (molding). K, is the leg, with the ornament (j) &c upon it.

Having thus described our new design of Cook Stove, what we claim as new & desire to secure by Letters Patent, is the ornamental design & configuration of cook stove plates, such as herein described & represented in the annexed drawing.
